UNITED STATES PATENT OFFICE.

JAMES WALTER ADAMS, OF SPRECKELS, CALIFORNIA.

CENTRIFUGAL ROLLER-MILL.

1,201,672.

Specification of Letters Patent. Patented Oct. 17, 1916.

Application filed March 9, 1914. Serial No. 823,456.

To all whom it may concern:

Be it known that I, JAMES WALTER ADAMS, a citizen of the United States, residing at Spreckels, in the county of Monterey and State of California, have invented 5 new and useful Improvements in Centrifugal Roller-Mills, of which the following is a specification.

My invention relates to improvements in 10 centrifugal roller mills, being of that type employing a plurality of suspended crushing rollers adapted to coöperate with a crushing or bull-ring for the purpose of pulverizing material such, for instance as 15 lime, etc.

The present invention is designed mainly as 20 an improvement on what is known as the Raymond mill, the specific improvements being in mechanism for directing the material to the crushing point, this mechanism being generally indicated as plow mechanism; a 25 change in the form of the conduit supplying air, and the employment of an adjustable device for controlling the degree of fineness of the material being discharged. Mills of this 30 type employ an air blast for the purpose of creating a circulation of air through the mill by means of which the powdered material is discharged while that portion of material 35 which is not crushed to the desired extent is returned to the crushing chamber to be again operated upon; this circulation of air is general throughout the crushing chamber, the air supply being through ports extending 40 tangential to the bull-ring, the result being that there is a tendency for the material to be blown about. Where this blowing action takes place at the crushing point, it will be readily understood that the maximum 45 capacity of the mill is materially reduced for the reason that even though the material is delivered in proximity to such point by plow mechanism, the air currents will act to blow a considerable portion of this material away from that point.

This is one of the principal difficulties inherent to the mills of this type in general use, and one of the objects of my invention is to materially decrease if not entirely 50 eliminate this difficulty.

In practice I have found that a mill embodying the features of the present invention and employing but two crushing rollers in place of the four generally employed, 55 will increase the efficiency of the mill from one hundred to one hundred and fifty per

cent., thus enabling a greatly increased output to be had with a decreased cost of manufacture and a decreased tendency to wear through a reduction in the number of active 60 elements employed. The change in the form of air conduit is by the provision of a baffle so positioned that when in service air will be introduced through the tangential passages alike, while its removal will enable 65 ready access to be had to the conduit for the purpose of cleaning without the necessity for removing large numbers of parts or casings. By employing an adjustable sleeve at the discharge end of the mill separator 70 the degree of fineness of the material being discharged can be readily regulated.

Other objects are to provide a construction which is simple and efficient in operation, durable in construction, and which can 75 be manufactured and maintained in service at a relatively low cost.

To these and other ends, the nature of which will be readily understood as the invention is hereinafter disclosed, said invention 80 consists in the improved construction and combination of parts hereinafter fully described, illustrated in the accompanying drawings, and more particularly pointed out in the appended claims.

In the accompanying drawings, in which 85 similar reference characters indicate similar parts in each of the views, Figure 1 is a vertical sectional view taken centrally through a mill constructed in accordance with my invention, parts being shown in elevation. Fig. 2 is a sectional view taken on the line 2—2 of Fig. 1. Fig. 3 is an enlarged detailed sectional view taken on the line 3—3 of Fig. 1. Fig. 4 is a fragmentary plan view of 90 the plow in position. Fig. 5 is a view in elevation of parts shown in Fig. 4, looking in the direction of the arrow in said figure. Figs. 6 and 7 are cross sections of the plow 95 taken on the lines 6—6 and 7—7 respectively of Fig. 5. Fig. 8 is a bottom plan view of the cover plate.

As heretofore referred to, the general arrangement of parts of the mill is similar to that employed in what is generally known as the Raymond mill an exemplification of which is shown in the patent to Albert Raymond, No. 881,262, dated March 10, 1908, and I do not, therefore, herein particularly describe the parts of the general mechanism 105 in detail, the general arrangement providing for a vertical shaft 10 suitably driven,

said shaft carrying a spider 11 in which are pivotally suspended journal boxes 12 carrying the shafts of crushing rolls 13 adapted to coöperate with the crushing or bull-ring 14, the arrangement being such that as the shaft rotates, centrifugal action will cause the rolls 13 to coöperate with the ring 14 in crushing the material delivered thereto. The ring 14 is mounted within a suitable 10 casing, the latter being enlarged outwardly to form an air conduit 15 extending annularly and having a portion of its inner wall formed with tangential passages 16 leading from the conduit into the interior of 15 the crushing chamber below the bull-ring 14. As will be seen in Fig. 2, these tangential openings are located at equally spaced points throughout such inner wall, and in order that a substantially equal distribution 20 of the air therethrough shall be had, I preferably employ a baffle 17 which may be removably positioned adjacent to a hand-hole 18, the presence of the baffle causing the air to travel solely in one direction through the 25 conduit, while its removal will enable the introduction of a suitable cleaning implement through the hand-hole 18 to enable a ready cleaning of the conduit to be had.

The separator portion of the mill is along 30 the lines indicated in the patent referred to, the circulation of air being through the annular space between the drums 19 and 20 and thence downward through the discharge opening 21, the latter being provided with a 35 sleeve 22, adjustable in suitable manner as by the use of the threaded rod 23, the position of the inner end of the sleeve controlling the amount of deflection of the air currents and consequently controlling the degree of fineness 40 of the material being discharged, this latter feature being one of the improvements which I have provided in connection with the Raymond mill. Similarly I employ a sleeve 24 adapted to move with the shaft 10, 45 this sleeve having its lower portion projecting outwardly, as at 24^a and which is adapted to carry the plow mechanism now to be described.

As in mills of this type, a plow is provided 50 for each crushing roll, but inasmuch as these structures are duplicates, I will specifically describe but one. Mounted on the flange 24^a is a radial arm 25 having a laterally extending portion 25^a. 26 designates a 55 plate carried by the arm 25, which plate preferably extends above the plane of said arm and which also has a downwardly projecting portion 26^a curved along the general lines of the shoe or plow presently described, 60 said part 26^a acting as a supporting member for the plow or shoe, this arrangement being more particularly shown in Figs. 3, 4 and 5. Secured to the plate 26 is a vertically extending plate 27 forming the major portion 65 of the inner wall of the plow cavity, this

plate extending into close proximity to the face of the crushing roll, and also having a laterally extending portion 27^a, the upper surface of which is substantially on the plane of the upper face of the bull-ring, said portion 27^a forming a support for the cover plate 28, the latter being provided with slots 28^a by means of which it may be adjusted on the said part 27^a. The cover plate forms the top of the plow cavity and projects rearwardly substantially to the crushing point, being positioned over the crushing roll, as shown in Fig. 4. The cover plate is provided with a reinforcing strip 28^b along its outer edge (see Fig. 8) where it is brought into close proximity to, if not actual contact with, the top of the bull-ring which it overlaps. The plow or shoe 30 projects forwardly of the plate 27, and extends rearwardly substantially to the crushing point, being cut away at the rear, as at 30^a (Fig. 4) to permit the roll 13 passing to its crushing position, but providing for a formation of the smallest space possible therebetween without actual contact between the plow and the crushing roll, the purpose being to eliminate as much as possible the passage of air currents therebetween, this portion of the shoe or plow being in close proximity to the crushing point and hence the point where 95 proper and complete delivery of the material to be crushed is to be had. At this particular point there is thus formed a substantially closed cavity, the walls of which are provided at the bottom by the plow, on the outer side by the bull-ring, on the inner side by the crushing roll, and on the top by the cover plate 28. This cavity is approximately free from air current disturbances, since the lower wall of the cavity (provided by the plow) is above the tangential openings 16, and the space between the roll and the plow is so small as to materially restrict, if not entirely prevent the passage of the currents therethrough under any degree 100 of pressure, simple leakage not materially affecting or disturbing the material being delivered to the crushing point. The walls of the cavity therefore also constitute an enclosed passageway through which the material to be crushed must pass to the crushing point.

The inner or active face of the plow or shoe is generally curved, cross sections of the shoe in Figs. 6 and 7 showing this face 120 30^b as curved in cross section, while the showing in Fig. 5 indicates a general inclination upwardly and rearwardly as indicated by the dotted line 30^c. The point of the plow projects downwardly approximately to the bottom of the crushing chamber and the rotation of the sleeve 24 causes the point to take up material deposited at the bottom of the crushing chamber. Owing to the curvature of the plow face, this ma- 125 130

terial is carried rearwardly without any tendency to clog or choke, there being an entire absence of corners or angles on the outer side of this plow cavity, the result 5 being that the material is led upwardly to the plane of the bull-ring and passes into contact with said ring in advance of the crushing point, said ring, as heretofore explained, forming the outer wall of the cavity 10 at this point. Consequently the material is brought to the crushing point in a continuous stream substantially uniform, being practically unaffected by the air currents and also being free from a choking or clogging 15 action which would have a tendency to break up the continuity of operation and possibly provide damage to the machine, the crushing point being located in close proximity to if not at the rear or discharge end 20 of the plow cavity. This discharge end of the cavity can be regulated to some extent by manipulation of the cover plate 28 the latter covering to a greater or less extent the space in advance of this crushing point 25 at will.

It will thus be seen that I have provided a plow structure which comprises the plow, its mounting, the plate 27 and the cover plate, and in which the mouth of the plow 30 cavity is located some distance in advance of the crushing roll and is relatively large, with the forward end of the plow acting as a protruding lip for the mouth, the lip being so formed in cross section as to gradually 35 direct the material taken up by its point into the mouth in a direction leading gradually toward the bull-ring, the lip having a shape which provides an outer wall to prevent the material being thrown outwardly by centrifugal action, and gradually 40 leading rearward to the plane of the bull-ring. The throat of the cavity is gradually contracted, being formed with practically no angles which would affect the free passage 45 of the material therethrough, and having the discharge end of the throat in such close proximity to the crushing point as to deliver substantially the entire quantity of material passing through the mouth and 50 throat to the action of the crushing roll. It will also be seen that while the plow projects forwardly and is provided with an outer wall, the particular shape of the plow is such that the discharge of air into the 55 chamber through the tangential openings can take place, this discharge at the front of the plow approaching the direction of travel of the plow and, being over the top of the outer wall, it will not act to force 60 the material from the lip; similarly, the undershape of the plow is such as will enable the air currents to pass thereunder into the chamber, these currents, however, being practically prevented from reaching the 65 throat of the cavity through the particular

formation of the rear of the plow as heretofore pointed out. Consequently not only will the plow provide for maximum efficiency, but its arrangement is such as to provide a minimum resistance to the entrance 70 of the air currents, so that practically the maximum efficiency of the latter will also be had, the result being that the efficiency of this type of machine is increased at least double, actual operations 75 demonstrating these facts, the operations being with a less number of crushing rolls than that usually employed with this type of apparatus. While I have shown and described what is believed to be the preferred 80 embodiment of the invention which will produce this result, it will be understood that changes and modifications therein may be found desirable or necessary to meet the various exigencies of use, and I therefore desire to be understood as reserving the right to make such changes or modifications as may be found necessary or desirable, in so far as the same may fall within the spirit and scope of the invention as expressed in 85 the accompanying claims.

Having thus described my invention, what I claim as new is:

1. In a centrifugal rolling mill, the combination with a bull-ring, and a crushing roll adapted to coöperate therewith by centrifugal action, of a plow, and a housing at the rear of said plow constituting with the adjacent portion of said bull-ring and said crushing roll a substantially inclosed 95 passageway to deliver material to the crushing point between said roll and bull-ring. 100

2. In a centrifugal rolling mill, the combination with the bull-ring, and a crushing roll adapted to coöperate therewith by centrifugal action, of a plow structure positioned in advance of the crushing roll, said structure having a passageway to deliver material to the crushing point, said bull-ring forming an outer wall of the passageway, said passageway gradually contracting 105 toward its discharge end. 110

3. In a centrifugal rolling mill, the combination with the bull-ring, and a crushing roll adapted to coöperate therewith by centrifugal action, of a plow structure positioned in advance of the crushing roll, said structure comprising a plow and means co-operating therewith to provide a plow cavity spaced from the forward end of the plow 115 with the bull-ring acting as one of the walls of the cavity, the throat of the cavity being contracted and having its discharge in proximity to the crushing point. 120

4. In a centrifugal rolling mill, the combination with the bull-ring, and a crushing roll adapted to coöperate therewith by centrifugal action, of a plow structure positioned in advance of the crushing roll, said structure comprising a plow and means co- 125

operating therewith to provide a plow cavity spaced from the forward end of the plow with the bull-ring acting as one of the walls of the cavity, said means including a cover plate overhanging the bull-ring and the crushing roll.

5. In a centrifugal rolling mill, the combination with the bull-ring, and a crushing roll adapted to coöperate therewith by centrifugal action, of a plow structure positioned in advance of the crushing roll, said structure comprising a plow and means co-operating therewith to provide a plow cavity spaced from the forward end of the plow with the bull-ring acting as one of the walls of the cavity, said means including a cover plate overhanging the bull-ring and the crushing roll, said plate being adjustable to vary its overhang of the roll.

20 6. In a centrifugal rolling mill, the combination with the bull-ring, and a crushing roll adapted to coöperate therewith by centrifugal action, of a plow structure positioned in advance of the crushing roll, said
25 structure comprising a plow and means co-operating therewith to provide a plow cavity spaced from the forward end of the plow with the bull-ring acting as one of the walls of the cavity, the rear of said plow
30 being recessed to receive the roll, whereby the plow may extend in proximity to the crushing point.

7. In a centrifugal rolling mill, the combination with the bull-ring, and a crushing roll adapted to coöperate therewith by centrifugal action, of a plow structure positioned in advance of the crushing roll, said structure comprising a plow and means co-operating therewith to provide a plow cavity spaced from the forward end of the plow with the bull-ring acting as one of the walls of the cavity, said plow having its material-receiving face curved in cross section with a portion forming the outer wall of the plow in advance of the cavity mouth.

8. In a centrifugal rolling mill, the combination with the bull-ring, and a crushing roll adapted to coöperate therewith by centrifugal action, of a plow structure positioned in advance of the crushing roll, said structure comprising a plow and means co-operating therewith to provide a plow cavity spaced from the forward end of the plow with the bull-ring acting as one of the walls of the cavity, said plow having its material-receiving face curved in cross section with a portion forming the outer wall of the plow in advance of the cavity mouth, said curved face being inclined rearwardly and upwardly toward the crushing point.

60 wardly toward the crushing point.
9. In a centrifugal rolling mill, the combination with the bull-ring, and a crushing roll adapted to coöperate therewith by centrifugal action, of a plow structure positioned in advance of the crushing roll, said

structure comprising a plow and means co-operating therewith to provide a plow cavity spaced from the forward end of the plow with the bull-ring acting as one of the walls of the cavity, said plow having its material-receiving face curved in cross section with a portion forming the outer wall of the plow in advance of the cavity mouth, said curved face being inclined rearwardly and upwardly toward the crushing point, the rear of the plow being recessed to receive the roll, whereby said face will extend in proximity to the crushing point. 70 75

10. In a centrifugal rolling mill, the combination with the bull-ring, and a crushing roll adapted to coöperate therewith by centrifugal action, of a plow structure positioned in advance of the crushing roll, said structure comprising a plow and means co-operating therewith to provide a plow cavity spaced from the forward end of the plow with the bull-ring acting as one of the walls of the cavity, said plow having its material-receiving face curved in cross section with a portion forming the outer wall of the plow in advance of the cavity mouth, said curved face being inclined rearwardly and upwardly toward the crushing point, said means including a cover plate adapted to overhang the bull-ring and crushing roll to extend said cavity to a point in proximity to said crushing point. 80 85 90 95

11. In a centrifugal rolling mill, the combination with the bull-ring, and a crushing roll adapted to coöperate therewith by centrifugal action, of a plow structure positioned in advance of the crushing roll, said structure comprising a plow and means co-operating therewith to provide a plow cavity spaced from the forward end of the plow with the bull-ring acting as one of the walls of the cavity, said plow having its material-receiving face curved in cross section with a portion forming the outer wall of the plow in advance of the cavity mouth, said curved face being inclined rearwardly and upwardly toward the crushing point, said means including a cover plate adapted to overhang the bull-ring and crushing roll to extend said cavity to a point in proximity to said crushing point, said cover plate being adjustable to control the amount of overhang. 100 105 110 115

12. In a centrifugal rolling mill, the combination with a crushing chamber and a bull-ring, and a crushing roll adapted to coöperate with said bull-ring by centrifugal action, the crushing chamber wall having a plurality of air-inlet openings positioned below said bull-ring, of a plow structure positioned in advance of said crushing roll, said structure comprising a plow having its under and outer surfaces sloping laterally away from the chamber wall adjacent said openings. 126 125 130

13. In a centrifugal rolling mill, the combination with a crushing chamber and a bull-ring, and a crushing roll adapted to co-operate with said bull-ring by centrifugal action, the crushing chamber wall having a plurality of air inlet openings positioned below said bull-ring, of a plow structure positioned in advance of said crushing roll and having a plow member extending forwardly and downwardly therefrom, said plow member diminishing in size in the direction of its extension and having its under and outer surfaces sloping laterally away from the chamber wall adjacent said openings. 15

In testimony whereof I affix my signature in presence of two witnesses.

JAMES WALTER ADAMS.
